UNITED STATES PATENT OFFICE.

JOHN KRALUND, OF BROOKLYN, NEW YORK, ASSIGNOR TO DOEHLER DIE CASTING COMPANY, A CORPORATION OF NEW YORK.

CASTING APPARATUS.

1,257,885.

Specification of Letters Patent. Patented Feb. 26, 1918.

Application filed September 10, 1915. Serial No. 49,857.

To all whom it may concern:

Be it known that I, JOHN KRALUND, a citizen of the United States, residing at the borough of Brooklyn, in the city of New York, county of Kings, and State of New York, have invented certain new and useful Improvements in Casting Apparatus, of which the following is a specification, reference being had therein to the accompanying drawings, which form a part thereof.

My invention relates to casting apparatus and more particularly to improvements in the type of pressure die casting apparatus described in Letters Patent No. 973,483 of October 25, 1910, to adapt said apparatus to the practice of the method or art invented by H. H. Doepler, application for Letters Patent upon which is filed simultaneously herewith.

The practice of said method or art requires that the molten metal be poured into a mold or die from a melting pot or crucible in which the metal to be poured is subjected to a temperature of substantially that of the fusing of the metal to be cast and that the metal be poured from within an inclosed chamber into which air or other fluid under high pressure is admitted to complete the casting operation. In this type of apparatus, it is essential that the chamber from which the metal is poured, be capable of being opened to admit the insertion or removal of the melting pot or crucible containing the molten metal and that said melting pot or crucible be rotatably mounted within said chamber to permit its being overturned to pour the metal therefrom.

The economical practice of said method or art requires the employment of a large number of melting pots or crucibles, all of which are simultaneously subjected to the desired temperature, and that these melting pots or crucibles be transferred one at a time from the furnace to the pressure chamber. The fact that the said chamber is opened to admit the melting pot or crucible requires the operator to hold the melting pot or crucible in position in the chamber during the closing thereof.

By my present invention, I provide an apparatus wherein the rotatable support for the melting pot or crucible is adapted to be successively used with a plurality of melting

pots or crucibles, thus facilitating the operation of the apparatus and providing an operative handle common to all of the melting pots or crucibles, and one, the temperature of which will remain such as not to interfere with the convenient handling of such melting pots or crucibles.

The said support is not only adapted for use in the pressure chamber but is also used in removing the melting pots or crucibles filled with the molten metal from the furnace and restoring them thereto, with a fresh charge of metal therein. The walls of the pressure chamber and said melting pot or crucible support, are so constructed as to sustain said support within said chamber while the chamber is being closed.

Inasmuch as the melting pot or crucible after being overturned is subjected to high pressure while within the said pressure chamber, I so construct it and its support that pressure applied to the bottom of said melting pot or crucible will be transmitted to and sustained by the support, in a manner to prevent the crucible being forced from said container.

The invention consists primarily in a casting apparatus embodying therein a sectional mold, a head forming a pressure chamber surmounting said mold and adapted to be opened, means forming a constricted passageway between said pressure chamber and the interior of said mold whereby the molten metal will tend to flow by gravity from said chamber to said mold, a melting pot or crucible, a support therefor comprising an operating handle, jaws pivotally mounted therein adapted to encircle and to detachably engage said melting pot or crucible and means whereby said jaws may be opened, the walls of said chamber having therein a bearing adapted to receive said support, and means whereby an elastic fluid under pressure may be introduced to said chamber to follow up the metal through said passageway and force the metal into the mold; and in such other novel features of construction and combination of parts as are hereinafter set forth and described and more particularly pointed out in the claims hereto appended.

Referring to the drawings:—
Figure 1 is a side elevation partly in verti-

cal section of a casting apparatus embodying my invention, the melting pot or crucible being shown in dotted lines;

5 Fig. 2 is a plan view thereof with the pressure chamber opened;

Fig. 3 is a top view of the melting pot or crucible and its support, the jaws of the support being opened and portions of the support being broken away; and

10 Fig. 4 is a side view of the melting pot or crucible and a portion of its support.

Like letters refer to like parts throughout the several views.

In the embodiment of my invention shown 15 in the drawings, two parts $a-b$ of a sectional mold supported upon guide rods $c-c'$ are shown, said sections being adapted to be separated in any desired manner, as by the lever mechanism d operative upon one of 20 said sections. The said sections $a-b$ each has therein, a portion of the opening into which the metal is to be forced, an ingate opening $a'-b'$ being provided in the face of 25 said sections $a-b$ respectively and extending substantially vertically. Surmounting and carried by the sections $a-b$ respectively are the two parts $e-f$ of a head, forming, when the parts $e-f$ are closed, a pressure chamber. 30 Opening into one of said sections e is a pipe g through which air under pressure is delivered to said chamber. This pipe g is controlled by a valve g' of the usual construction, to permit the venting of the chamber after the casting has been made. The action 35 of the lever mechanism d in holding the two parts of the mold and head together is supplemented by a clamp h which is set after the parts are brought together. At i I have 40 shown an ejector mechanism by means of which the casting is drawn or forced from the mold.

The ingate $a'-b'$ is enlarged adjacent the pressure chamber so as to form a sub-chamber into which the metal is poured before 45 flowing into the ingate.

The rods $c-c'$ are so supported as to be capable of being moved to incline the mold from the vertical if desired, as by means of the pivotal supports j for one of the mold 50 sections as b and the vertically adjustable standard k carrying the end of said rods. This construction, however, is not essential to the invention in an apparatus of this character, although it is desirable as adapting the device for the making of castings wherein it is not desirable to have the ingate extend vertically.

The chamber $e-f$ has a bearing l in the wall thereof.

60 The structure heretofore described is that described in the Letters Patent above referred to and I make no claim of invention thereto, my invention relating more particularly to the combination with this structure 65 of the specific mechanism by means of which

the molten metal is introduced within the chamber formed by the head parts $e-f$. In the apparatus above referred to, the molten metal was introduced into the pressure chamber by means of a ladle, the handle of 70 which was rotatably mounted in the bearing l , the molten metal being dipped from a crucible, and the desired measured quantity thereof poured into this ladle before it was mounted in the said bearing l . 75

In the practice of the method or art above referred to it is impracticable to melt the metal in a ladle of the character shown in the aforesaid Letters Patent, and my invention relates to those modifications in the 80 apparatus by which the metal may be brought to the desired temperature in a melting pot or crucible of a size adapted to hold a single charge for the apparatus and be conveniently removed from the furnace to 85 the pressure chamber so as to permit it to be poured directly from the melting pot or crucible in which it is conditioned, into the mold.

In the accompanying drawings, I have 90 shown at m a small melting pot or crucible and at n a handle therefor which is adapted to be detachably connected therewith. This handle has pivotally connected therewith, oppositely disposed jaws $n'-n^2$ adapted to 95 conform to, and engage the outside of said melting pot or crucible. Each of these jaws $n'-n^2$ is provided with a short heel as n^3-n^4 pivotally connected together and with a push rod n^5 slidable in a longitudinal bore in the handle n , suitable lost motion being provided in one or both of said heels. Said rod is provided with an enlarged head n^6 and acting against said head with a normal tendency to close the jaws 105 $n'-n^2$ is a spring n^7 seated in a socket in said handle.

The handle n is provided with an enlarged portion n^8 adapted to extend across and act as a seal for the bearing l in the wall of the 110 pressure chamber in a manner to prevent leakage at this point.

When the melting pot or crucible is overturned, it acts more or less as a shield between the discharge end of the pipe g and the ingate to the mold, to prevent splashing of the metal by reason of the impingement of the air jet directly thereagainst. The force of this jet is sufficiently great to preclude the possibility of the jaws $n'-n^2$ holding the melting pot or crucible solely by friction. To prevent the melting pot being forced by the air jet from the said jaws, I provide the said melting pot or crucible with a shoulder o , preferably an annular rib 115 adapted to be engaged by the jaws $n'-n^2$. To guard against a possible dropping of the melting pot or crucible, I also provide a shoulder p , also preferably an annular rib, 120 parallel with and spaced away from the 130

shoulder o a sufficient distance to permit the jaws $n'-n^2$ to enter between these rings or annular ribs.

To facilitate the handling of the melting pot or crucible, when placing it within the pressure chamber, I provide the inside wall at one side of the chamber with a stirrup q adapted to receive a trunnion q' carried by one of the jaws as n' and provide the outer 10 wall adjacent the bearing l with a second stirrup r adapted to receive the handle n .

The operation of the herein described apparatus is substantially as follows:—

When a die has been properly set with 15 its ingate communicating with the pressure chamber, a plurality of melting pots m , each containing metal of the desired bulk are placed in a furnace and subjected to a temperature approximating that of the fusing 20 point of the metal contained in the melting pot or crucible, for a sufficient time to reduce the metal to a molten condition. The two parts $e-f$ forming the pressure chamber having been separated, the jaws $n'-n^2$ 25 of the support for the melting pot or crucible are opened by pressing the rod n^5 inwardly against the tension of the spring n^7 .

The jaws $n'-n^2$ while opened, are then 30 inserted within the furnace in a position so that, as they close, they will encircle a melting pot or crucible and engage same between the shoulders or ribs $o-p$ thereon. The melting pot or crucible thus engaged is then transferred to the pressure chamber, the 35 handle n being inserted in the bearing l with the enlarged portion n^8 adjacent said bearing on the inside thereof. The parts $e-f$ and the die parts $a-b$ are then closed and locked by means of the lever d and clamp h .

40 The stirrups $q-r$ are provided merely to assist the operator in inserting the melting pot or crucible and its support in the pressure chamber and to simplify the operation of closing the said chamber and the mold 45 or die.

When the pressure chamber and the mold or die have been properly closed, the handle n is rotated overturning the melting pot or crucible m , pouring the metal contained 50 therein into the bottom of the pressure chamber where it will be collected and concentrated in the sub-chamber and flow by gravity toward the mold or die through the ingate to the mold or die. Immediately 55 after overturning the melting pot or crucible air is admitted to the pressure chamber by the opening of the valve g' , thus accelerating the flow of the metal into the mold and compacting and compressing it therein.

60 When the melting pot or crucible is overturned and the air is admitted to the pressure chamber, the bottom or side wall of said melting pot or crucible will be presented toward the air inlet and thus act as 65 a shield to prevent a fluid jet impinging

upon the molten metal in the bottom of said pressure chamber. As air or other fluid at high pressure is used, there would be a tendency of a fluid jet directed against the said melting pot or crucible, to force it from between the jaws $n'-n^2$ were it not for the shoulders or ribs $o-p$ between which the said jaws are seated.

The melting pot or crucible may be made of any desired material which will withstand the temperatures to which it is subjected.

It is not my intention to limit the invention to the precise details of construction shown in the accompanying drawings, it being apparent that such may be varied without departing from the spirit and scope of the invention.

Having described the invention, what I claim as new and desire to have protected by Letters Patent is:—

1. A casting apparatus embodying therein in a sectional mold, a head forming a pressure chamber surmounting said mold and adapted to be opened, means forming a constricted passageway between said pressure chamber and the interior of said mold whereby the molten metal will tend to flow by gravity from said chamber to said mold, a melting pot or crucible, a support therefor comprising an operating handle, jaws mounted thereon adapted to encircle and to detachably engage said melting pot or crucible and means whereby said jaws may be opened and closed, the wall of said chamber having therein a bearing adapted to receive said support, and means whereby an elastic fluid under pressure may be admitted to said chamber to follow up the metal through said passageway and force the metal into, and compress it in, the mold.

2. A casting apparatus embodying therein a sectional mold, a head forming a pressure chamber surmounting said mold and adapted to be opened, means forming a constricted passageway between said pressure chamber and the interior of said mold whereby the molten metal will tend to flow by gravity from said chamber to said mold, a melting pot or crucible, a support therefor comprising an operating handle, jaws pivotally mounted thereon adapted to encircle and to detachably engage said melting pot or crucible and means whereby said jaws may be opened and closed, the wall of said chamber having therein a bearing adapted to receive said support, and means whereby an elastic fluid under pressure may be admitted to said chamber to follow up the metal through said passageway and force the metal into, and compress it in, the mold.

3. A casting apparatus embodying therein in a sectional mold, a head forming a pressure chamber surmounting said mold and adapted to be opened, means forming a con-

- stricted passageway between said pressure chamber and the interior of said mold whereby the molten metal will tend to flow by gravity from said chamber to said mold, 5 a melting pot or crucible, a support therefor comprising an operating handle, jaws pivotally mounted thereon adapted to encircle and to detachably engage said melting pot or crucible, a rod slidably mounted 10 in said handle, and operative connections between said rod and said jaws respectively and a spring acting between said rod and said handle whereby said jaws are automatically closed, the wall of said chamber 15 having therein a bearing adapted to receive said support, and means whereby an elastic fluid under pressure may be admitted to said chamber to follow up the metal through said passageway and force the metal into, 20 and compress it in, the mold.
4. A casting apparatus embodying therein in a sectional mold, a head forming a pressure chamber surmounting said mold and adapted to be opened, means forming a constricted passageway between said pressure chamber and the interior of said mold whereby the molten metal will tend to flow by gravity from said chamber to said mold, 25 a melting pot or crucible, a support therefor comprising an operating handle, jaws pivotally mounted thereon adapted to encircle and to detachably engage said melting pot or crucible, each of said jaws being provided with a short arm or heel, a rod 30 slidably mounted in said handle and pivotally connected with each of said arms or heels, lost motion being provided to permit the oscillation of said arms or heels, and a spring acting between said handle and 35 said rod whereby said jaws will be automatically closed, the wall of said chamber having therein a bearing adapted to receive said support, and means whereby an elastic fluid under pressure may be admitted to said 40 chamber to follow up the metal through said passageway and force the metal into, and compress it in, the mold.
5. A casting apparatus embodying therein in a sectional mold, a head forming a pressure chamber surmounting said mold and adapted to be opened, means forming a constricted passageway between said pressure chamber and the interior of said mold whereby the molten metal will tend to flow by 45 gravity from said chamber to said mold, a melting pot or crucible, a support therefor comprising an operating handle, jaws mounted thereon adapted to encircle and to detachably engage said melting pot or crucible, a trunnion carried by the end of said 50 jaws and means whereby said jaws may be opened and closed, the wall of said chamber having therein a bearing adapted to receive said support, a stirrup within said chamber adapted to receive said trunnion, and 55

means whereby an elastic fluid under pressure may be admitted to said chamber to follow up the metal through said passageway and force the metal into and compress it in, the mold.

6. A casting apparatus embodying therein in a sectional mold, a head forming a pressure chamber surmounting said mold and adapted to be opened, means forming a constricted passageway between said pressure 70 chamber and the interior of said mold whereby the molten metal will tend to flow by gravity from said chamber to said mold, a melting pot or crucible, a support therefor comprising an operating handle, jaws 75 mounted thereon adapted to encircle and to detachably engage said melting pot or crucible, a trunnion carried by the end of said jaws and means whereby said jaws may be opened and closed, the wall of said chamber 80 having therein a bearing adapted to receive said support, a stirrup within said chamber adapted to receive said trunnion and a second stirrup adjacent said bearing adapted to receive said handle and guide it and support it in said bearing while the mold is open and means whereby an elastic fluid under pressure may be admitted to said chamber to follow up the metal through said 85 passageway and force the metal into, and compress it in, the mold.

7. A casting apparatus embodying therein in a sectional mold, a head forming a pressure chamber surmounting said mold and adapted to be opened, means forming a constricted passageway between said pressure chamber and the interior of said mold whereby molten metal will tend to flow by gravity from said chamber to said mold, a melting pot or crucible having a shoulder thereon 90 presented toward the top thereof, a support therefor comprising an operating handle, jaws mounted thereon adapted to encircle and detachably engage said melting pot or crucible above said shoulder, and means 95 whereby said jaws may be opened and closed, the wall of said chamber having therein a bearing adapted to receive said support, and means whereby an elastic fluid under pressure may be admitted to said chamber to follow up the metal through said passageway and force the metal into, and compress it in, the mold.

8. A casting apparatus embodying therein in a sectional mold, a head forming a pressure chamber surmounting said mold and adapted to be opened, means forming a constricted passageway between said pressure chamber and the interior of said mold whereby molten metal will tend to flow by gravity 100 from said chamber to said mold, a melting pot or crucible having oppositely disposed shoulders and spaced apart, a support therefor comprising an operating handle, jaws mounted thereon adapted to encircle and 105

detachably engage said melting pot or crucible between said shoulders, and means whereby said jaws may be opened and closed, the wall of said chamber having
5 therein a bearing adapted to receive said support, and means whereby an elastic fluid under pressure may be admitted to said chamber to follow up the metal through said passageway and force the metal into, and
10 compress it in, the mold.

In witness whereof I have hereunto affixed my signature in the presence of two subscribing witnesses this 1st day of September, 1915.

JOHN KRALUND.
